US0D1081440S

(12) **United States Design Patent** (10) **Patent No.:** **US D1,081,440 S**
(45) **Date of Patent:** **** Jul. 1, 2025**

(54) **WATCH STRAP**

(71) Applicant: **Cailing Dai**, Lufeng (CN)

(72) Inventor: **Cailing Dai**, Lufeng (CN)

(**) Term: **15 Years**

(21) Appl. No.: **29/997,554**

(22) Filed: **Apr. 8, 2025**

(51) **LOC (15) Cl.** **11-01**

(52) **U.S. Cl.**

USPC **D11/3**

(58) **Field of Classification Search**

USPC D10/32; D11/1-5

CPC A44C 5/0053

(57) **CLAIM**

The ornamental design for a watch strap, as shown and described.

DESCRIPTION

FIG. 1 is a front, right and top perspective view of a watch strap, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the watch strap in its use state; and,

FIG. 10 is another perspective view thereof in its use state. The broken lines shown in the drawings illustrate portions of the watch strap that form no part of the claimed design.

1 Claim, 10 Drawing Sheets
